Primary Examiner — Katie Jane Stofko(74) *Attorney, Agent, or Firm* — Evan Law Group LLC(57) **CLAIM**

The ornamental design for a group of tamales with colored husks, as shown and described.

DESCRIPTION

FIG. 1 is a front, top and right side perspective view of a group of tamales with colored husks showing my new design;

FIG. 2 is a front elevation view thereof;

FIG. 3 is a back elevation view thereof;

FIG. 4 is a top plan view thereof;

FIG. 5 is a bottom plan view thereof;

FIG. 6 is a left side elevation view thereof; and,

FIG. 7 is a right side elevation view thereof.

The drawings are lined for color. FIGS. 1-7 include stippling and line shading to indicate the presence of contrasting colors. The smaller stippled shading, larger stippled shading and line shading shown in FIGS. 1-7 represent a contrasting appearance.

The broken lines shown represent unclaimed subject matter and form no part of the claimed design.
